UNITED STATES PATENT OFFICE.

FREDERICK WINK, OF PHILADELPHIA, PENNSYLVANIA, ASSIGNOR TO
THOMAS DOLAN, OF SAME PLACE.

DESIGN FOR SHAWL-PATTERN.

Specification forming part of Design No. 6,081, dated August 20, 1872.

Specification describing a Design for a
Shawl - Pattern, invented by FREDERICK
WINK, of Philadelphia, Pennsylvania.

Design for a Shawl-Pattern.

The figure in the accompanying drawing
shows sufficient of a shawl-pattern to illustrate
my design, the principal features of which are
the wide stripe A and narrow stripe B. The
latter is composed of five parallel ribs, *a*, *b*, *c*,
d, and *e*, of equal width, the whole of which
are crossed by straight, diagonal, and zigzag
lines, by the combination of which the pec-
uliar pattern illustrated is produced. The
stripe A has a central bar, *f*, composed of a
series of ornamented ribs, having the same
general characteristics as the stripe B. The

stripe A is also ornamented near its outer
edges by narrow ribs *g* and *h* of the character
represented.

Irrespective of the colors employed, I claim—

1. The design for the stripe B, substantially
as shown and described.
2. The design for the stripe A, substantially
as described and illustrated.
3. The design for the whole pattern, includ-
ing the stripes A and B.

In testimony whereof I have signed my name
to this specification in the presence of two sub-
scribing witnesses.

FRED. WINK.
